UNITED STATES PATENT OFFICE.

ALBERT B. CHAPMAN, OF SILVER CREEK, AND FRANK A. SHOEMAKER, OF BUFFALO,
NEW YORK; SAID SHOEMAKER ASSIGNOR TO SAID CHAPMAN.

ROTARY MOTOR.

No. 927,639.

Specification of Letters Patent.

Patented July 13, 1909.

Application filed April 17, 1908. Serial No. 427,760.

To all whom it may concern:

Be it known that we, ALBERT B. CHAPMAN and FRANK A. SHOEMAKER, citizens of the United States, and residents of Silver Creek, 5 in the county of Chautauqua and State of New York, and of Buffalo, in the county of Erie and State of New York, respectively, have invented certain new and useful Improvements in Rotary Motors, of which the 10 following is a specification.

This invention relates to rotary motors and more particularly to that type of rotary motors known as a turbine. Its primary object is the production of a motor of such type, 15 in which buckets or impact-elements are removably attached to the body-portion of a turbine-wheel so that one size of buckets or impact-elements may be employed in motors of different sizes, but since motors of this 20 type are used for all kinds of work and are built in small sizes as well as very large sizes, we find that, for best results, the buckets or impact elements used in the smallest size of motors should be used only in engines up to a 25 certain size or horse power, and that, as the motor increases in size or horse-power, the buckets should be enlarged; each size of buckets or impact-elements being employed in motors of different sizes or horse-power 30 between certain limits. In this manner, four sizes of buckets or impact-elements would serve admirably for all sizes of motors capable of use for all ordinary purposes.

Another object of our invention is the production of a simple and efficient motor, in 35 which few parts are used in addition to the buckets or impact-elements and in which the latter are rigidly held to the body of the turbine-wheel by a single element.

Another object of our invention is the provision of a plurality of chambers having each a turbine-wheel and means of exhaust, the means of exhaust of the first or primary chamber serving as the inlet for the motive 40 fluid of the second chamber if only two chambers are employed, and if more than two chambers are employed, each succeeding chamber is in communication with the preceding chamber through the medium of the 45 exhaust of said preceding chamber, the motive-fluid exhausted from each chamber, except the last, is directed against the turbine-wheel of the succeeding chamber or chambers, as the case may be.

A further object of our invention is to en-

large the successive chambers and their contained turbine-wheels and to so construct the walls of the chambers that each chamber extends partly into its succeeding chamber, if there be such.

60

Still further objects of our invention are, to so arrange the turbine-wheels with relation to the preceding chambers, if there be such, that the buckets or impact-elements of each wheel surround the peripheral wall of the 65 chamber directly preceding; to provide the primary chamber with an annular steam-chest so that the motive-fluid entering said chest may issue therefrom at different points and be directed simultaneously and con- 70 stantly against different buckets of the turbine-wheel in said chamber; and to otherwise improve on engines of this type as and in the manner to be described hereinafter.

With these objects in view, the invention 75 consists in the construction, arrangement, and combination of parts to be hereinafter described and particularly pointed out in the appended claims.

In the drawings,—Figure 1 is a front elevation of my improved motor or engine. Fig. 2 is a vertical section, taken on line 2—2, Fig. 1. Fig. 3 is an enlarged sectional view taken through a portion of line 2—2, Fig. 1. Fig. 4 is a section taken on line 4—4, Fig. 3. Fig. 5 is a transverse section taken on line 5—5, Fig. 2. Fig. 6 is a section similar to Fig. 2, showing our invention in modified form.

Referring now to the drawings in detail, 90 like letters of reference refer to like parts in the several figures.

The reference letter A designates the cylindrical casing which may be supported in any practicable manner, but is herein shown as having supporting legs a. In the embodiment of our invention shown in Figs. 1 to 5, the casing is shown as comprising two parts A¹, A², bolted together to form a piston receiving chamber A³. Part A¹ has an overhanging flange a¹ which forms the peripheral wall of the casing and near the bottom of the casing it is provided with an exhaust-opening a². Part A² is cored out to provide a steam chest B into which an inlet-opening b is tapped to receive a feed-pipe for the motive-fluid. Said steam-chest has an annular extension B¹ which extends into the chamber A³ and has its outer peripheral wall b¹ provided with openings, preferably at regular 100 105 110

intervals, into which fluid-nozzles C are secured in any approved manner; said nozzles being arranged tangentially around said peripheral wall.

5 A motor shaft D is journaled axially in the ends or heads of the casing, and part A², which serves as one of said heads is removable to permit access to the parts within the casing. Said shaft is stepped to provide two 10 shoulders d, d¹; the portion between said shoulders receives the turbine-wheel E which bears against the shoulder d and it is threaded to receive a securing-nut F whereby said wheel is held in position. Shoulder d¹ abuts 15 against the inner face of one of the heads of the casing and prevents endwise movement of the shaft in one direction while a spacing-element or washer G interposed between the other head of the casing and the turbine-wheel, serves to prevent endwise movement 20 of the shaft in the opposite direction.

The turbine-wheel comprises the body-portion H which is herein shown in the form of a disk, but any other form may be given 25 the same if desired. Its peripheral edge is screw-threaded to receive an annulus I which is of sufficient width to overhang the disk and surround the annular extension B¹ of the steam chest and its inner periphery is tapered from its screw threaded portion to its 30 free edge, for a purpose to appear presently.

Bucket-units or impact-elements J are arranged in a circular series within the annulus. Each bucket or impact-element comprises a 35 body-portion j whose outer surface j¹ is curved and inclined from its inner edge to its outer edge to correspond with the taper of the annulus and a scoop-like portion j² projecting inward from said body-portion. 40 The end edges of the body-portions of said buckets are cast or machined in radial lines and are placed edge to edge around the inner surface of said annulus. The annular space between the annular extension B¹ of the 45 steam-chest and the annulus is of sufficient size to provide the necessary clearance for the buckets in their movement over the fluid-nozzle, which latter are so disposed that the motive-fluid (which may be water, steam, 50 gas, vapor, air, or any other propelling fluid) is directed against the impact-elements to compel rotation of the turbine-wheel.

In order to secure the buckets or impact-elements in position, they are inserted in the 55 annulus in circular series from the wide end and forced toward the narrow end; the annulus is then threaded onto the body-portion of the turbine-wheel, and by means of suitable machinery or tools securely fastened. 60 This causes the inner edges of the buckets to be forced against said body-portion of the wheel and simultaneously drawn together; thereby assuring a secure wedging of the buckets into position.

65 In the construction shown in Fig. 6, we

have shown a compound motor or engine, in which K designates the primary chamber, and K¹, K² the secondary chambers. Although we have shown two secondary chambers, one or more than two may be employed, if desired. The construction of the casing of the primary chamber and its contained turbine-wheel is similar to corresponding parts in the motor shown in Figs. 1 to 5, except that the peripheral wall has an outstanding flange L forming part of the enclosure for the adjoining secondary chamber, and the same reference letters designating the various parts shown in said figures, also apply to the parts of the casing and wheel of the primary chamber. In Fig. 6, the successive chambers are made successively large and the casing of the primary chamber extends partly into the second chamber, while the casing of the latter extends partly into 80 the third chamber, each casing forming part of the inclosure on the next succeeding chamber. The casing of the second chamber is bolted to the outstanding flange L of the primary chamber and it is itself provided with 85 an outstanding flange M to which the casing of the third chamber is secured. This arrangement may be extended to provide any number of additional chambers.

The peripheral wall of the casing of the 90 primary chamber has fluid-nozzles N through which the motive-fluid is exhausted and these nozzles direct the motive-fluid against the impact elements of a turbine-wheel O in the 95 second chamber. The peripheral wall of the casing of said second chamber has fluid-nozzles P through which the motive-fluid is exhausted from said second chamber and directed against the impact-elements of a turbine wheel R in the third or last chamber, 100 which latter has a final exhaust S. The turbine-wheels O and R may be similar to that in the primary chamber and the three wheels are secured to a shaft T.

Having thus described our invention, what 110 we claim is,—

1. A turbine-wheel comprising a body-portion provided on its periphery with screw-threads, a flange threaded onto said body and over-hanging thereon, and a series of impact-elements held in position by said flange. 115

2. A turbine-wheel comprising a body-portion provided on its periphery with screw-threads, and a flange threaded onto said screw-threaded periphery and carrying impact-elements. 120

3. A turbine-wheel comprising a body-portion provided on its periphery with screw-threads, an annulus threaded onto said screw-threaded periphery and overhanging one side of said body-portion, and bucket-units held to the inner periphery of the overhanging portion of said annulus. 125

4. A turbine-wheel comprising a body-portion, an over-hanging annulus threaded 130

- onto said body-portion and having its inner peripheral surface tapered, and impact-elements arranged in circular series and drawn together by said annulus.
5. A turbine-wheel comprising a body-portion, an over-hanging annulus secured to said body-portion and having its inner peripheral surface tapered, and bucket-units arranged in circular series against the tapered surface of said annulus and drawn against the body-portion by said annulus.
6. A turbine-wheel comprising a body-portion, an overhanging annulus adjustable on said body-portion and having its inner surface tapered, and impact-elements in circular series drawn together and against said body-portion by said adjustable annulus.
7. A turbine-wheel comprising a body-portion, an overhanging annulus held on said body-portion and having its inner surface tapered, and bucket-units held in position against the inner tapered surface of said annulus, each bucket-unit having its outer surface curved and tapered to conform to or approximately conform to the tapered surface of said annulus.
8. A turbine-wheel comprising a body-portion, a removable annulus and a circular series of impact-elements held wholly within said annulus. 30
9. A turbine-wheel comprising a body-portion, an annulus removable on said body-portion and extending therefrom to overhang one side, and a series of impact-elements held against the inner peripheral surface of said annulus. 35
10. A turbine-wheel comprising a body-portion, an overhanging annulus removably held to said body-portion, and impact-elements in circular series rigidly held by said annulus and surrounded thereby. 40

In testimony whereof, we have affixed our signatures in the presence of two subscribing witnesses.
